UNITED STATES PATENT OFFICE.

STEPHEN PALMER, OF LANSINGBURG, NEW YORK.

SASH-CORD GUIDE.

SPECIFICATION forming part of Letters Patent No. 370,647, dated September 27, 1887.

Application filed April 28, 1886. Serial No. 200,421. (No model.)

To all whom it may concern:

Be it known that I, STEPHEN PALMER, a resident of Lansingburg, in the county of Rensselaer and State of New York, have invented 5 certain new and useful Improvements in Combined Sash-Cord Guide and Mortise-Marker; and I do hereby declare that the following is a full, clear, and exact description of the invention, that will enable others skilled in the 10 art to which it appertains to make and use the same, reference being had to the accompanying drawings, and to the letters of reference marked thereon, which form a part of this specification.

15 Similar letters refer to similar parts in the several figures therein.

My invention relates to improvements in combined sash-cord guide and mortise-marker; and it consists of a sash-cord guide having the 20 face-edges of the pulley-case curved to form a series of arcs of circles and provided with marking-spurs integral therewith and located centrally of the several arcs along one or both of the face-edges.

25 The objects of my invention are fully set forth in connection with the following description.

Figure 1 of the drawings is a face view of my improved device. Fig. 2 is a side view of 30 same. Fig. 3 is a plan view of a portion of a window-jamb marked for boring to form a mortise.

I am able to make use of any form of pulley case or shell having its face-edges curved 35 to form a series of arcs of circles adapted to fit a corresponding series of auger-holes forming the mortise adapted to receive the case.

I have shown a plain well-known case, D, provided with face-edges curved to form the 40 arcs of circles C C along each edge of the case on opposite sides of the sheave or pulley P, which pulley is interiorly mounted upon an axle supported by the case. Centrally of each arc is a little spur, a', projecting from the face-edge along one or both sides of the case.

45 Instead of spurs notches a², cut in the edges, may be employed, as shown on one side.

The advantages of the curved face-edges adapted to fit a series of auger-holes are well 50 known to builders.

To make the required mortise it is only nec-

essary to bore holes in the jamb or other object of a size to correspond with the arcs C, the two end holes being of sufficient depth to let the plate in flush with the surface of the 55 jamb and the intermediate holes of a depth to admit the pulley and case D, no chiseling being required. If the holes are bored at the proper distances from each other, the face-edges will accurately fit and present a very 60 neat and finished appearance; conversely, if the holes are not properly located, the edges will not fit. To successively and accurately measure the distance for each hole as it is bored would require much time and care and 65 render the operation as laborious as the old method of using the chisel.

By means of the spurs a' along one face-edge I am able to mark the center of each hole by a single blow upon the opposite edge, and it 70 is only necessary to successively insert the screws of the bit or auger in the marks so made when the holes are bored to insure the proper position of the holes relatively to each other.

The device is so placed that the spurs on one face-edge rest upon the window-jamb, and a slight blow given upon the opposite edge produces small indentations or marks b in the 75 jamb; or by drawing the device across the jamb 80 the latter will be scratched by the spurs, and by inserting the screw of the bit in these marks or scratch lines holes indicated by dotted lines can be formed which the face-edges of the plate or case will exactly fit.

85 The number of arcs employed may be varied as desired. I have shown five, the two end ones having screw-holes and forming parts of a face-plate by which the device is secured in place. By combining the guide and marker 90 in one implement I am able without additional expense to provide each sash-cord guide with a marker which is always at hand ready for use, thereby avoiding the expense of providing separate implements for the purpose 95 and the inconvenience of keeping such implements within reach when preparing mortises for sash-cord guides.

What I claim as new, and desire to secure by Letters Patent, is—

100 As a new article of manufacture, a combined sash-cord guide and mortise-marker consist-

ing of a sash-cord guide having the face-edges of the pulley-case curved to form a series of arcs of circles, and provided with marking-spurs integral therewith and located centrally 5 of the several arcs along one face-edge, substantially as described, and for the purposes set forth.

In testimony whereof I have hereunto set my hand this 26th day of April, 1886.

STEPHEN PALMER.
